METHOD AND APPARATUS FOR DISTRIBUT-
ING LIQUEFIED GASESOdd A. Hansen, Kenmore, and Peter M. Riede,
Buffalo, N. Y., assignors to The Linde Air Prod-
ucts Company, New York, N. Y.

Application December 6, 1941, Serial No. 421,902

9 Claims. (Cl. 62—1)

This invention relates to an apparatus for and a method of transporting and dispensing gas material, such as oxygen, which has been liquefied. It is particularly concerned with providing with such gas, consumers whose demands are small relatively to that required by some of the large industrial plants.

Heretofore in the case of such smaller consumers it has been common practice to deliver the material as a gas under high pressure in steel cylinders which involves the transport back and forth of considerable dead weight in the containers themselves, such dead weight being high in proportion to the amount of gas delivered.

On the other hand, in the case of larger consumers a common practice has been to deliver the gas material in the liquid phase in special transport trucks and tank cars with the liquid container mounted permanently thereon. This necessitates, however, that such large consumers have considerable equipment for storing the liquid and for converting it into gas as desired for use, including suitable controls therefor, the cost of which equipment would be prohibitively burdensome if the quantity of gas material used was small.

The present invention proposes an economical and simple way of supplying the demands of such smaller consumers. It contemplates the transport of the material to the consumer as a liquid and involves the provision and use of a novel combined container and converter of small capacity. The unit is self-contained and of a character and size such that it may be readily transported on a normal truck and readily moved about manually at the plant where the gas is to be consumed. The unit is capable of generating and supplying gas under adequate pressure for general industrial uses and is provided with full controls to render it a complete independent container and source of gas supply. It is designed to withstand relatively high pressures and, in conjunction particularly with appropriate receivers which may readily be associated therewith, to take care of periods of non-use or shut-downs of fairly long duration. The connections are such as to enable it to be quickly connected for service or disconnected when exhausted of gas, and easily handled and recharged.

Other objects of the invention will in part be obvious and will in part appear hereinafter.

The invention accordingly comprises the several steps and the relation of one or more of such steps with respect to each of the others, and the

apparatus embodying features of construction, combinations of elements and arrangement of parts which are adapted to effect such steps, all as exemplified in the following detailed disclosure, and the scope of which invention will be indicated in the claims.

For a fuller understanding of the nature and objects of the invention reference should be had to the following detailed description taken in connection with the accompanying drawings, in which:

Fig. 1 is a view partly in section of a mobile unit illustrative of principles of the invention;

Fig. 2 is a diagrammatic showing of a typical installation of the unit including the circuits and connections of the unit; and

Fig. 3 is a unit similar to that of Fig. 1 but including gas receivers removably mounted on the common mobile support.

Referring now particularly to Fig. 1, there is depicted a portable cold converter in which 10 denotes an inner vessel adapted to contain liquefied gas and the gas as evaporated, the walls of which are of a thickness and strength adapted to withstand substantial pressures such as 400 lbs. per square inch. The vessel 10 is provided with an outer shell 11 spaced a substantial distance therefrom to provide an intermediate vacuum space 12. The container unit also includes an outer protective shell or casing 13. The container vessels 10 and 11 are preferably spherical in shape, and the outer shell 13 may be of a generally cylindrical shape with a dome-shaped top 14 as shown. The space 12 between the two vessels may be filled with suitable insulating material such as magnesium carbonate, but in the interests of maintaining the dead weight at as low a value as reasonably practicable and thereby provide increased gas material capacity for a given size and total weight of charged container, it is preferred to employ a straight high vacuum. In that case the outer surface of the vessel 16 and the inner surface of vessel 11 will preferably be highly polished.

The vessels 10 and 11 are provided with concentric neck portions 15 and 16 respectively, projecting upwardly through an opening in the dome 14 of the protective outer shell. A plate 17 is secured in the upper end of the neck portion 16 and has a counterbore 18 into which extends the upper end of the neck portion 15 of the inner container. The joints between the plate 17 and the neck portions 16 and 15 are of course made gas-tight, the junctures being made by any convenient means as welding. A cap assem-

bly indicated generally at 19 is adapted to be removably secured to the top, as by stud bolts 20 threaded into the plate 17, including nuts 21 threaded on the upper end of the stud bolts. The assembly 19 includes various elements, some of which project down into the interior of the container 10, as will be described more in detail shortly.

The unit, as a whole, is made mobile through suitable means. In the particular construction disclosed this is accomplished through a supporting base 30 upon which the unit is secured, the base being provided with a pair of wheels 31 permanently attached thereto and an attachable truck jack 32 provided with a pair of wheels 33. The truck jack may be of any well known type suitable to be wheeled into place and operated to elevate the unit off the legs 34 when the unit is to be moved. For this purpose the truck jack has a bolster portion 35 having an opening adapted to receive the pintle 36 projecting downwardly from the frame 38.

The size and weight of the unit may be varied to suit the conditions within the range in which it may be readily moved about by a single normal individual. As an example, it has been found that a unit employing an inner liquid containing vessel comprising a sphere about two feet in diameter is well within that range and at the same time provides a considerable capacity for gas material.

Returning now to the cover assembly 19 and referring also to Fig. 2, which shows the connections diagrammatically, it will be seen that this assembly unit includes an upper sleeve 40 from which projects down into the liquid container a supporting rod 40a, carrying a suitable float means 41 at the lower end suitably connected to operate a rod 42 which in turn operates through a suitable mechanism a liquid level indicator 43. Secured also in the assembly 19 and projecting down into the liquid container 10 is a second tube 44 containing electric wire connections to an electrical heater unit 45. In fluid communication with the interior of sleeve 40 and thereby with the interior of container 10 is a pressure responsive device 46 comprising a switch adapted to control the electrical heater circuit to maintain a predetermined pressure within container 10. This may be adjusted to maintain any desired pressure within the capacity of the container, as, for example, to open the circuit when a pressure of 110 lbs. per sq. inch is reached and to close the switch when the pressure drops to 100 lbs. There is also provided a safety release valve 47 and, if desired, a bursting disk 48. The circuit to the electrical heater may be plugged into a suitable source of electric energy through the conveniently arranged socket 49, an electric cord 50 so connected being shown in Fig. 2 at the left. The electrical heater circuit also includes a thermostatically operated switch 51 exposed to the temperature within the container 10 so that when the latter becomes exhausted of liquid the circuit to the heater will be broken automatically. Both the electrical heater and the thermostat are enclosed in a suitable sheath, and the tube 44 is suitably sealed so that none of the gas material comes in direct contact with the electric units or connections. A gas outlet line is shown at 52 communicating with the interior of the container in any suitable manner as through the interior of sleeve 40. This outlet includes a shut-off valve 53 and suitable coupling 54. A main filling and withdrawal line 60

is provided having a shut-off valve 61 and coupling 62. The line 60 has a pipe extension 63 projecting downwardly into the container to approximately the bottom of the neck portion. This prevents liquid entering through 60 from being blown out with gases escaping through pipe 52 in cases where the gases are vented off during filling. The assembly 19 is provided with an outer shell 64 which may be removed independently for access to the nuts 21 to remove the assembly as a whole when desired.

As illustrative of the advantages of the type of unit comprised in this invention and of the method of employing it, the following example is given. Assuming that there is a unit to be charged with liquid oxygen at the manufacturing plant, the unit will be connected to the source of supply through the coupling 62 and line 60. If the container is cold it can be filled by pressure means, as through a pump, without venting gas which may remain or be formed in the container since the incoming cold liquid will tend to condense any such gas. If, however, the container is warm or because of any other circumstances it is desired to vent off the gases, this may be done through the line 52 and the discharged gas taken to a holder for compression into cylinders. After the container 10 has been fully charged, the valve 61 may be closed and the container preferably maintained sealed during subsequent transportation. Some heat leakage into the container contents will occur during transport, but ordinarily this will not be sufficient to produce a pressure in excess of the service pressure, and therefore no loss will occur. The unit will be loaded on a suitable automotive truck which may be of an ordinary plain platform type along with, if desired, other like units or other equipment such as the high pressure cylinders of gas heretofore referred to in the event that a delivery thereof to certain customers is also to be made. Upon arrival at the consumer's plant one or more units, as desired, will be lifted from the truck to the receiving platform. This may be done by a suitable derrick which may be mounted, for example, on the delivery truck or, if conditions permit, a jack truck such as shown at 32 in Fig. 1 may be applied under the unit and the unit manually wheeled off the truck and positioned as desired.

In Fig. 2 there is shown a typical illustrative arrangement which may be employed at the consumers. It may be assumed that the unit A at the left in Fig. 2 is in use and is connected to one or more gas cylinders 65 by means of suitable piping as the flexible hose connection 66 having couplings 66' and 66''. The line will have a valve 67 therein adjacent the receiver. As shown, a service line 68 having therein a valve 69 leads from the receivers 65. It may be assumed also, for example, that the unit B at the right has been in previous service and the contents exhausted. The unit B therefore will be disconnected and replaced by a new charged unit, and the valves 61 and 67 to the newly attached unit opened. As soon as the unit A is exhausted the new unit at B is placed into active operation, which requires merely the plugging in of the electrical heater connection.

The exhausted unit B which had been disconnected is loaded onto the truck and returned for refilling to the manufacturing plant. The empty units may, of course, be open to the atmosphere and the pressure released therefrom, but in accordance with the principles of the present pro-

posed method and the character of unit provided, the valve may remain closed and the unit returned to the manufacturing plant and the gas remaining withdrawn and conserved prior to recharging. The amount of oxygen delivered to a customer in any case may be readily determined and kept account of by weighing of the charged container as it leaves the plant and reweighing the container as returned from the customer.

Referring again to the operation at the consumers, the construction and arrangement permit intermittent withdrawal and shutdowns without loss of gas, except perhaps when the shutdown is unusually long. This advantage results from the fact that the liquid container is well insulated and is capable of withstanding an internal pressure of approximately 400 lbs. per sq. in., which is considerably in excess of the 100 lbs. per sq. in. normal working pressure. Thus if a shutdown occurs, normal heat leak to the container will cause the pressure to rise rather than the safety device to blow with an accompanying loss of gas. Upon resumption of withdrawal the pressure will gradually drop until it returns to the normal working pressure where it is maintained by the electrical heater means. The capacity to permit long shutdown periods without loss is increased by the receivers 65 which hold some of the gas generated by heat leak during the period. By adding receiver capacity, as by increasing the number, the permissible shutdown period without loss of gas can be extended as desired.

The receivers perform an additional function which is to act as an atmospheric type super-heater when the unit is in operation. The gas issuing from the converter is very cold having been vaporized directly from the liquefied gas. It is noted that the boiling point of liquid oxygen at 100 lbs. per sq. in. gauge is -157°C . Before feeding the gas to the oxygen consuming equipment it should be heated to approximately room temperature. This is conveniently done by passing the gas through the receivers. The large surface area and high heat capacity supply the necessary heat transfer picking up the heat from the surrounding atmosphere.

It will be understood that the description as to the units is merely illustrative and that the units disclosed are capable of use in many different ways appropriate to the conditions encountered at various consumers. The unit, for example, may be moved around the consumer's plant from one location to another and be brought closely adjacent the point where gas is to be consumed, thereby eliminating in such cases any need for extensive pipe connections but at the same time making readily and quickly available at various points quite remote from each other a source of gas under pressure adequate for normal industrial use. If desired, the units may remain at the consumer's plant and the liquid brought to it and transferred thereto at any convenient point.

In Fig. 3 there is shown another unit similar in general to that of Fig. 1 but in which there is directly mounted thereon one or more gas cylinders 80, two such being shown, the one in the foreground being partly broken away. The cylinders are preferably removable, being held in place normally by any suitable means, which in the present case includes a pair of chains 81, one hooked to each of a pair of handles 82 arranged on opposite sides of the container shell. Such handles preferably form a part also of the unit

shown in Fig. 1 and may serve as a means to which a chain fall may be readily attached for lifting the unit by a small derrick, as on and off a truck. The coupling 62 enables the gas discharge line from the container to be quickly connected or disconnected to the receivers, suitable valves such as indicated at 83 and 84 being provided for controlling the connections to the receivers and to the supply line 85.

10 The assembly shown in Fig. 3 comprises a complete supply unit including reserve gas containers in the line and may be maintained intact as such if desired. It will be advantageous in some cases, however, when the liquid in a unit is exhausted to remove the gas receivers therefrom and assemble them on a freshly charged container, which may be accomplished, of course, without releasing the gas from the receivers. This manner of operation requires less equipment.

15 Since certain changes in carrying out the above method and in the constructions set forth, which embody the invention may be made without departing from its scope, it is intended that all matter contained in the above description or shown 20 in the accompanying drawings shall be interpreted as illustrative and not in a limiting sense.

Having described our invention, what we claim as new and desire to secure by Letters Patent, is:

1. A portable apparatus for containing liquefied 25 gases and for generating and supplying gas under pressure directly therefrom, comprising an insulated pressure container, a mobile support therefor forming a unitary part of said apparatus, an electrical heating means in said container for conveying heat to the liquid to gasify same as desired for industrial use, a controlling device for said electrical heating means responsive to the pressure in said container for maintaining a predetermined pressure therein, a thermostatic device 30 exposed to the temperature within said container and adapted to control said heating means to prevent an excessive temperature, and valved 35 supply and withdrawal connections for said container.

2. A portable unit for containing and transporting liquefied gases and for supplying directly 40 gas under pressure, said unit being of a size adapted to be carried on a transport means and provided with means for readily moving it at the 45 consumers independently of such transport means, and said unit comprising an insulated pressure container for the liquefied gases, a supporting base therefor, valved supply and withdrawal connections for said container, electrical 50 heating means for supplying heat directly to the liquid to gasify the liquid and supply gas as required for use, means for automatically controlling the supply of heat to maintain a predetermined maximum gas pressure, and means for controlling said heating means to prevent excessive 55 temperature.

3. A portable unit for containing and transporting liquefied gases and for supplying directly 60 gas under pressure, said unit being of a size adapted to be carried on a transport truck and provided with means for readily moving it at the consumers independently of such transport truck, and said unit comprising an insulated pressure container for the liquefied gases, a wheeled 65 supporting base therefor forming a permanent part of said unit, a gas receiver mounted on said base, valved supply and withdrawal connections for said container including a gas connection to said receiver, electrical heating means for supplying 70 heat directly to the liquid to gasify the liquid and

supply gas as required for use, means for automatically controlling the supply of heat to maintain a predetermined maximum gas pressure, and means for readily connecting said electrical heating means to a source of power at the selected place of use.

4. A portable unit for containing liquefied gases and for supplying gas under pressure directly therefrom for industrial use, said unit being of a size and character adapted to be carried on a transport truck and provided with means for readily moving it at the consumers independently of said transport and comprising an insulated pressure container for the liquefied gases, valved supply and withdrawal connections for said container, electrical heating means for supplying heat directly to the liquid to gasify the liquid and supply gas under pressure suitable for industrial use as required, means for automatically controlling the supply of heat to maintain a predetermined pressure, and a thermostatic control in the circuit to said electrical heater exposed to the temperature within said container.

5. A portable apparatus for containing liquefied gas and supplying gas under pressure directly therefrom, comprising an insulated container adapted to withstand substantial pressures suitable for general industrial use having an opening for the insertion of associated equipment, and a closure assembly for said opening adapted to be applied or removed as a unit including an electrical heater adapted to project into the interior of said container, a control device therefor connected to control said heater to maintain a predetermined gas pressure, a liquid level indicator and valved conduit connections for the supply or withdrawal of fluid all forming part of said unit, and means for releasably securing said closure assembly in place against the pressure maintained in said container.

6. A portable unit for containing liquefied gases and for supplying gas under pressure directly therefrom, comprising a supporting frame, an insulated pressure container mounted thereon, automatically controlled electrical heating means within said container for conveying heat to the liquid in said container to gasify the liquid as required, a gas receiver removably mounted on said supporting frame, and valved gas connections from said container to said receiver readily

releasable to permit the easy removal of said receiver.

7. A portable unit for containing liquefied gases and for supplying gas under pressure directly therefrom, comprising a mobile supporting frame, an insulated pressure container mounted thereon, automatically controlled means for conveying heat to the liquid in said container to gasify within said container the liquid as required, a gas receiver removably mounted on said supporting frame, and valved gas connections from said container to said receiver readily releasable to permit the easy removal of said receiver, said unit not exceeding a size such that it may be readily moved about manually on said mobile supporting frame.

8. A portable apparatus for containing liquid oxygen and for generating and supplying oxygen gas under pressure directly therefrom, comprising an insulated pressure container, a mobile support therefor forming a unitary part of said apparatus, an electrical heating means in said container for conveying heat to the liquid to gasify same as desired for use, means responsive to pressure in said container connected to control said heating means for maintaining a predetermined pressure in said container, a thermostatic device exposed to the temperature within said container and adapted to control said heating means to prevent an excessive temperature, and a valved withdrawal connection and means for filling said container with said liquid oxygen.

9. A unit for holding highly volatile liquefied gas and for generating and supplying gas under pressure directly therefrom comprising an insulated pressure container, an electrical heating means in said chamber for conveying heat to the liquefied gas to gasify same, means responsive to pressure in said container connected to control said heating means to maintain automatically a predetermined pressure in said container, a thermostatic device exposed to the temperature within said container and connected to render said heating means inoperative when the temperature rises to a predetermined limit, a valved gas withdrawal connection, and means for filling said container with the liquefied material.

ODD A. HANSEN.
